(57) **CLAIM**

The ornamental design for a baby proof vent cover as shown and described.

DESCRIPTION

FIG. 1 is top perspective view of a babyp proof vent cover;

FIG. 2 is a bottom perspective view thereof;

FIG. 3 is a top plan view thereof;

FIG. 4 is a bottom plan view thereof;

FIG. 5 is a right side view thereof;

FIG. 6 is a left side view thereof;

FIG. 7 is a front elevation view thereof;

FIG. 8 is a rear elevation view;

FIG. 9 is a perspective view of the babyp proof vent cover shown in FIG. 1 in a first configuration of use; and,

FIG. 10 is a perspective view of the babyp proof vent cover shown in FIG. 1 in a second configuration of use.

The broken lines in FIGS. 9 and 10 depict environmental subject matter that forms no part of the claimed design.
